TRAINING SEAT

Knud A. Jensen and Lew W. Throssel, both of Eldora, Iowa, assignors to Infanseat Company, Eldora, Iowa, a corporation of Iowa

Continuation of design application Ser. No. 82,439, Nov. 2, 1964. This application Sept. 13, 1965, Ser. No. 86,956

Term of patent 14 years

(Cl. D4—5)

FIGURE 1 is a perspective view of a training seat showing our new design;

FIGURE 2 is a bottom perspective view thereof; and

FIGURE 3 is a fragmentary, reduced-scale, side elevational view thereof.

The dominant features of our design reside in the portions shown in full lines.

This application is a continuation of application serial No. D. 82,439 filed November 2, 1964, now abandoned.

We claim:

The ornamental design for a training seat, as shown and described.
